Attorney.

UNITED STATES PATENT OFFICE.

MARIUS VASSELON, OF ST. ETIENNE, FRANCE.

GAS-RADIATOR.

1,375,987.

Specification of Letters Patent. Patented Apr. 26, 1921.

Application filed March 6, 1920. Serial No. 363,766.

To all whom it may concern:

Be it known that I, MARIUS VASSELON, citizen of the Republic of France, residing at 21 Rue Michel Servet, St. Etienne, Loire, 5 in the Republic of France, have invented new and useful Improvements in Gas-Radiators, of which the following is a specification.

This invention relates to a heater or radiator designed in such a manner that it possesses a very large heating surface under a reduced volume. It may be heated by lighting gas, acetylene gas and other gases or a mixture of air with vapors of suitable 15 fuels such as wood spirit, etc.

In the annexed drawing:

Figure 1 is a front face of a heater designed in accordance with the invention.

Fig. 2 is a vertical cross section of the 20 same on a smaller scale.

This apparatus comprises several horizontal rows of tapered tubes *a* mounted in staggered relation in a sheet metal casing comprising two parallel walls *c*, *c*¹, the lateral and upper edges of which may be connected by means of hooks, seams, rivets or by welding to a sheet metal band suitably bent or curved so as to form the sides *d* and top *d*¹ of the casing.

30 The walls *c*, *c*¹ are provided with openings to receive the tubes *a*, the ends of which are flanged externally upon said walls. These tubes may be made of iron, steel, copper or other suitable metal and are obtained by 35 drawing out tubes or by means of sheet metal blanks which are rolled and welded. Their shape is that of a conic frustum the large base of which is located at the front part of the heater as is clearly shown in 40 Fig. 2.

The front wall *c* is not extended down to the base part *e* of the apparatus. This base part which is preferably made of cast-iron supports the rear wall *c*¹ and the side walls 45 *d* which are fastened thereto by any suitable means.

A parabolic reflector *f* is provided at the bottom of the heater underneath the whole series of tubes *a* and extends along the entire length of the casting *e* the height of 50 said reflector being somewhat greater than that of the opening *o* between the casting *e* and the lower edge of the front wall *c*.

A burner constituted by a gas pipe *b* provided with holes at its top part extends parallel to the casting *e* and its position is such

that the flames produced occupy the focus of the parabolic surface constituting the reflector so that the radiating effect is completely utilized. This pipe *g* is supported 60 in the side walls *d* through which it passes and is provided outside the heater with an extension *b* in which is mounted a Bunsen injector *t* connected to the supply gas pipes by means of a flexible pipe in the usual 65 manner.

Another wall *c*² is provided at the rear of the apparatus at a suitable distance from the wall *c*¹. The metal band forming the side and top walls *d* and *d*¹ is sufficiently 70 wide to extend to said wall *c*² and close same on three sides thereof, the fourth side being constituted by the casting *e*, the latter being however cut out at this part so that the chamber *h* formed between the walls *c*¹, *c*² is 75 in communication with the outer air.

The top *d*¹ of the apparatus is provided with a circular opening to receive a pipe *j* for discharging the spent gases. The pipe *j* is closed at the top and carries a cylindrical 80 casing *k* having at a suitable point a pipe connection *l* leading to the chimney or the outside. The pipe *j* is provided with holes *m* oppositely located with respect to the pipe *l* and opening into the casing *k*. 85

The operation of the apparatus is as follows:

The gas burner being lighted, the tubes *a* will be heated to a high temperature by the flames of said burner and by the radiation 90 of the reflector. The front and rear walls *c*, *c*¹ and the side walls *d* will reach also a certain temperature. The outer air around the apparatus is thus heated by its contact with the very large heating surface obtained by 95 said apparatus. Moreover the air which is sucked into the chamber *h* enters into the tubes *a* through the small end thereof and goes out therefrom through the large end at the front of the apparatus, thus producing a continuous flow of hot air as long as the heater is in use.

Besides, the burnt gases flow upwardly toward the top of the heater through the pipe *j*, thence through the holes *m* into the annular space in the box *k* from which they escape through the pipe *l*. Consequently, these pipes *j* and *l* and the box *k* are also brought to a high temperature and constitute additional heating surfaces which will 105 contribute to the warming of the room in which the apparatus is placed.

It will be noted that on account of the arrangement of the casing with the staggered rows of tubes *a* and the location of the gas tube *g* the whole volume of the burning gases is obliged to flow around the tubes *a* which act as baffles in order to reach the outlet pipes *j* and *l*, which avoids every escapement of these gases from the apparatus into the room together with the many drawbacks of the generality of apparatus heretofore used.

The apparatus described yields a much greater heating power than the apparatus now commonly used having the same space and a similar consumption of fuel.

The number of tubes *a* may be varied as desired as may be the length and diameter thereof according to the heating surface required. The general dimensions may be also varied. In the big sizes, several gas burners *g* may be used instead of a single one.

Having now described my invention, what I claim as new and desire to secure by Letters Patent is:

- 25 1. A gas radiator for heating purposes comprising in combination a base part, a sheet metal casing supported and having its bottom formed by said base member, a plurality of horizontally staggered rows of tubes extending transversally from the front wall to the rear wall of the casing and opened at both ends, an opening in the front part of the casing underneath said tubes, a perforated gas pipe burner supported between the tubes and the base member and adapted to heat the tubes, said burner being connected to the gas supply, a parabolic reflector extending from side to side of the casing at the rear of said opening, and a burner, the focus line of which is adapted to coincide with the center line of the flames issuing from the burner, and an outlet at the top of the casing adapted to discharge the spent gases.
- 40 2. A gas radiator for heating purposes comprising in combination a base part, a sheet metal casing supported and having its bottom formed by said base member, a plurality of horizontally staggered rows of

tubes extending transversally from the front wall to the rear wall of the casing and opened at both ends, said tubes tapering rearward, an opening in the front part of the casing underneath said tubes, a perforated gas pipe burner supported between the tubes and the base member and adapted to heat the tubes, said burner being connected to the gas supply, a parabolic reflector extending from side to side of the casing at the rear of said opening and burner, the focus line of which is adapted to coincide with the center line of the flames issuing from the burner, and an outlet at the top of the casing adapted to discharge the spent gases, a second casing having for its front wall the rear wall of the first casing, said second casing being supported by the base member, and an air entrance at the bottom of said second casing.

3. A gas radiator for heating purposes comprising in combination a base part, a sheet metal casing supported and having its bottom formed by said base member, a plurality of horizontally staggered rows of tubes extending transversally from the front wall to the rear wall of the casing and opened at both ends, an opening in the front part of the casing underneath said tubes, a perforated gas pipe burner supported between the tubes and the base member and adapted to heat the tubes, said burner being connected to the gas supply, an outlet pipe having its lower end connected with an opening in the top wall of the casing, and its upper end closed, lateral openings on one side in the wall of said outlet pipe, a casing surrounding the top part of said outlet pipe into which open the said lateral openings and a pipe connecting a part of the casing opposite to said lateral openings to the point of discharge.

In testimony whereof I have signed my name to this specification in the presence of two subscribing witnesses.

MARIUS VASSELON.
